UNITED STATES PATENT OFFICE

MATTHIAS LEISSE, OF DUISBURG-MEIDERICH, GERMANY

CONTAINER

Application filed October 23, 1926, Serial No. 143,681, and in Germany November 4, 1925.

The present invention relates to a container for plastic substances such as ointments, pastes, and the like which are withdrawn by squeezing.

5 Containers for this purpose are already known in which a wall of the container is guided piston-like in the other part of the container, the withdrawal of the contents being effected by the inward movement of one 10 part of the container. Such containers are, however, unsatisfactory for the reason that it is almost impossible to secure a tight sliding fit, and in addition to the heavy pressure necessary for effecting the withdrawal of the 15 contents, where the pressure is not applied exactly centrally, the movable part of the container is forced sideways and thus caught.

Furthermore, it has been proposed to make a container from a rigid wall and a collapsible 20 wall, the latter consisting of a special substance which can be easily shaped, the contents of the container being withdrawn by pressure upon the collapsible wall. Such containers are, however, very awkward to handle. 25 As the contents are withdrawn irregularities on the face of the container are formed whereby the difficulties of effecting the removal of the contents are accentuated.

Other known and similar containers such, 30 for example, as a container in which the side walls consist of a material folded after the manner of a concertina, likewise fail to fulfil practical requirements. Furthermore, they do not give the contents of the container air-tight protection and do not admit of the ready 35 and complete withdrawal of the contents.

The present invention has for its object to provide a box-shaped container from which the contents can be squeezed and which can 40 be produced in bulk at a small cost, which, furthermore, gives airtight protection to the contents, and which lastly enables the whole contents to be expelled in a very simple manner. Moreover, the invention has for its object 45 to secure the withdrawal of the whole of the contents by the simple application of slight pressure.

According to the invention the container 50 consists of a rigid wall or part of determined shape and an oppositely disposed collapsible

wall, the shape of which can be altered in such a way that by local pressure in determined position upon the collapsible wall, the latter automatically alters to the shape of the rigid wall or part as the contents of the container 55 continue to be withdrawn, and when the container is quite empty the collapsible wall lies flat against the rigid wall. The collapsible wall is advantageously formed of a central pressure part and one or more annular parts 60 provided concentrically thereto, which parts are hingedly or flexibly connected together and to the pressure plate so as to permit of their being flattened out, radial channel-shaped depressions being provided in the separate annular surfaces to equalize the stresses 65 imposed by pressing out the shape-changing or collapsible wall.

The collapsible wall of the container is made from suitable material—such as aluminum, tinned plate or tin, or cardboard, celluloid or the like—simply and cheaply by presses, stamping machines or similar tools. The flexible or hinge-like parts are advantageously formed by scoring the material. 70 The contents may be withdrawn through one or more openings by slight local pressure in a central position upon the collapsible wall. The complete removal of the contents of the receptacle is effected by the uniform local 75 pressure upon the central part of the collapsible wall. A closure for the container may consist of a cone which is provided in the central pressure part of the collapsible wall in such manner that by exerting pressure 80 upon the cone the outlet is opened, and as the pressure is increased the flattening movement of the collapsible wall is produced whereby the contents are squeezed out. In 85 this way the quantity of the substance which is required from the container can be easily wiped off and applied directly upon a brush, or otherwise withdrawn, while immediately upon the pressure being relaxed a tight closure 90 is produced.

The invention is illustrated by way of example in the accompanying diagrammatic drawings, in which

Figure 1 is a section through the container, 100

with the walls in their initial position and with a maximum capacity or content;

Figure 2 is also a section through the container after the contents have been completely pressed out;

Figure 3 is a partial plan; and

Figure 4 is a section through the channel-shaped depressions and thickened parts of an annular part of the collapsible wall.

10 In the drawings 10 is the lower rigid wall of the container. Its shape is similar to that of the upper shape-changing wall of the receptacle after it has been flattened. The upper wall of the container consists of a 15 conical arched pressure plate or part 8, to which is connected the annular part 12 by a hinge-like or flexible part 3 produced by scoring the wall. A further hinge-like or flexible part 2 provides the integral connection of the annular part 12 to a further annular part 13. The upper wall of the container is produced integrally from material that can be shaped by the application of pressure, whereby the two annular parts 12, 13 form, 25 with respect to each other and to the other surfaces of the container, an angle providing a large space within the container (Figure 1). The annular parts 12 and 13 are provided with radial channel-shaped depressions 14 which equalize the pressure in the upper part of the receptacle, when the latter is flattened towards the bottom of the container. The rigid wall of the container is connected to the shape-changing wall by a 30 joint 9. Immediately adjacent to the joint 9 the annular part 13 is provided with a hinge-like or flexible part 1.

The cone or valve 4 is disposed in the opening 5 of the pressure part 8, a leaf spring 7 40 pressing the cone upwardly and thereby closing the container. The cone 4 is provided on its upper face with a pressure pin 6 by means of which the cone 4 can be depressed, whereupon the substance can issue through 45 the annular space which is thus provided between the cone 4 and the opening 5.

The upper part 10 of the receptacle is provided on the arch-shaped surface opposite to the pressure part 8, with a depression 50 11 into which the cone can pass.

It will thus be understood that the container described comprises a rigid wall having a concavity on its inner face and an oppositely disposed collapsible wall connected at 55 its peripheral edges with the coincident peripheral edges of the rigid wall so as thus to provide a completely enclosed cavity between the respective walls; and that the collapsible wall has on its inner face a concavity and is 60 adapted to be deformed so that when substantially the whole contents of the container are expelled the collapsible part of the collapsible wall comes to lie in contact with the rigid wall of the container. Thus in the illustrated construction the collapsible wall on

its being deformed to expel the contents of the container is bent respectively on circular lines near the peripheral edge between the respective annular parts 13 and 12 and between the annular part 12 and the central rigid part of the collapsible wall, and that the alternate radial projections and recesses in the surrounding collapsible part of the collapsible wall serve for the distribution of pressure in deformation.

The container according to the invention is operated as follows:—

The container is filled either through the cone 4, which is held back by suitable means, or before the joining together of the upper and lower parts. If pressure is applied by the pin 6 to the filled and closed container, the cone 4 first moves downwardly and opens the annular outlet. Any further slight increase of pressure is transmitted by the spring 7 to the pressure part 8, which moves downwardly in a straight line, whereby a portion of the substance in the container corresponding in volume to the space displaced, is squeezed out. Upon further local pressure being applied to the part 8, the annular parts 12 and 13 are flattened and change their position automatically and gradually from an angle into a straight line. When the pressure part 8 has reached a position upon the opposite arch of the lower, rigid wall of the container, the two annular parts 12 and 13 come to lie exactly on the wall 10, as shown in Figure 2, that is to say, the receptacle is completely emptied by the close contacting of the shape-changing wall of the container with the rigid wall.

In Figure 2 a brush is illustrated as the means for removing that part of the contents of the container that may have been expelled through the central outlet.

It will be understood that the invention is not limited to the construction illustrated in the drawings. The number and disposition of the separate annular surfaces, as also the shape of the pressure part, are inessential features of the invention.

The shape-changing wall of the container may consist of one or more connected layers of material. Instead of providing channel-shaped depressions for taking up the pressure which is produced in the flattening operation, radially disposed perforations may be provided in the annular parts, the perforations being closed by means of an underlay of resilient material.

Instead of the closure hereinbefore described and illustrated in the accompanying drawings, any other suitable closure devices may be used.

I claim:

1. A container for plastic substances such as pastes, ointments and the like of the type in which the contents are expelled by squeezing, comprising in combination a rigid wall 130

- having a concavity on its inner face and a collapsible wall connected to the said rigid wall near their respective oppositely disposed peripheral edges, the said collapsible wall 5 having radial channel-shaped projections and recesses and a concavity on its inner side, said projections and recesses being adapted on the external application of pressure to contract or expand in succession and to come finally in 10 contact with the inner face of the said rigid wall, substantially as hereinbefore described.
2. A container for plastic substances such as pastes, ointments and the like of the type in which the contents are expelled by squeezing, comprising in combination a rigid wall having a concavity on its inner face and a collapsible wall connected to the said rigid wall near their respective oppositely disposed peripheral edges, the said collapsible wall 15 having radial channel-shaped projections and recesses and an annular concavity on its inner side, said projections and recesses being adapted on the external application of pressure to contract or expand in succession and to come finally in 20 contact with the inner face of the said rigid wall, substantially as hereinbefore described.
- 25 3. A container for plastic substances such as pastes, ointments and the like of the type in which the contents are expelled by squeezing, comprising in combination a rigid wall having a concavity on its inner face and a collapsible wall connected to the said rigid wall near their respective oppositely disposed peripheral edges, the said collapsible wall 30 having radial channel-shaped projections and recessions and consisting of a central rigid part adapted for the application and distribution of pressure and an integral and annular surrounding part having on the inside an annular concavity, the said surrounding annular part being adapted on the application of pressure to the central part to contract or expand in succession permitting the internal 35 face of the surrounding annular part to come in contact with the inner face of the said rigid wall, substantially as hereinbefore described.
4. In a container as specified in claim 3 a valve seating on an inner face surrounding a central hole in the central part of the collapsible wall, said valve having a part extending outwardly and adapted to be opened by pressure applied at the outside and a spring adapted normally to maintain the said valve 40 in its closed position, substantially as hereinbefore described.
- 45 5. A container for plastic substances such as pastes, ointments and the like of the type in which the contents are expelled by squeezing, comprising in combination a rigid wall having a concavity on its inner face and a collapsible wall connected to the said rigid wall near their respective oppositely disposed peripheral edges, the said collapsible wall 50 having a central rigid part in which an outlet is provided and an integral surrounding part forming on the inner side a concavity the said surrounding part of the collapsible wall being formed of two annular parts adapted to bend with reference to each other and to the central rigid part and to the said rigid wall and being also provided with an alternate series of radial projections and recesses, substantially as hereinbefore described. 70
6. A container as specified by claim 1, in which the concavity of the rigid wall is provided within a convexity thereof, said convexity being similar to the concavity on said collapsible wall. 75
7. A container for plastic substances such as pastes, ointments and the like in which the contents are expelled by squeezing comprising in combination a rigid part having the form of a receptacle for said plastic substances and a collapsible part connected to said rigid part to form a cover therefor, said collapsible part consisting of a central rigid member and a plurality of annular members hinged to each other by score lines, said collapsible part being adapted on the external application of pressure upon it to contract and expand in succession and to come gradually in contact with said rigid part. 80
8. A container for plastic substances, such as pastes, ointments and the like of the type in which the contents are expelled by squeezing, comprising in combination, a rigid part having the form of a receptacle for said plastic substances, and a collapsible wall associated with said rigid part to form a closure therefor, said collapsible wall consisting of a rigid central member and a plurality of annular members, said annular members having each a set of radially directed depressions 85 adapted to hingedly connect said annular members with each other and with said rigid central member along circular score lines and permitting contraction and expansion of said annular members along the circular score line 90 therebetween during deformation of said collapsible wall on the external application of pressure thereon. 100
9. A container as specified by claim 1 having the central rigid member provided with an aperture, and a closing member adapted to resiliently close said aperture in inoperative condition of the container and to open said aperture upon application of pressure to said closing member. 105
- 110 10. A container as specified by claim 8, having the central rigid member provided with a valve adapted to resiliently close said container in inoperative condition thereof, thus permitting the discharge of the contents 115 from said container upon application of an external pressure on said valve. 120
